(57) **CLAIM**

The ornamental design for a casing for an ammunition magazine for a rifle, as shown and described.

DESCRIPTION

FIG. 1 is a left/top/rear perspective view of the casing for an ammunition magazine for a rifle.

FIG. 2 is a left plan view of the casing for an ammunition magazine for a rifle.

FIG. 3 is a right plan view of the casing for an ammunition magazine for a rifle.

FIG. 4 is a front plan view of the casing for an ammunition magazine for a rifle.

FIG. 5 is a rear plan view of the casing for an ammunition magazine for a rifle.

FIG. 6 is a top plan view of the casing for an ammunition magazine for a rifle.

FIG. 7 is a bottom plan view of the casing for an ammunition magazine for a rifle.

FIG. 8 is a right/top/front perspective view of the casing for an ammunition magazine for a rifle.

FIG. 9 is a right/bottom/front perspective view of the casing for an ammunition magazine for a rifle.

FIG. 10 is a left/bottom/front perspective view of the casing for an ammunition magazine for a rifle.

FIG. 11 is a left/top/front perspective view of the casing for an ammunition magazine for a rifle.

FIG. 12 is a left/bottom/rear perspective view of the casing for an ammunition magazine for a rifle.

FIG. 13 is a right/top/rear perspective view of the casing for an ammunition magazine for a rifle; and,

FIG. 14 is a right/bottom/rear perspective view of the casing for an ammunition magazine for a rifle.
